UNITED STATES PATENT OFFICE.

HENRY A. HOUSE, OF BRIDGEPORT, CONNECTICUT.

RECOIL-CHECK FOR VEHICLES.

No. 915,440.

Specification of Letters Patent. Patented March 16, 1909.

Application filed January 25, 1907. Serial No. 354,001.

To all whom it may concern:

Be it known that I, HENRY A. HOUSE, a citizen of the United States, and a resident of Bridgeport, in the county of Fairfield and State of Connecticut, have invented certain new and useful Improvements in Recoil-Checks for Vehicles, of which the following is a specification.

My invention relates to recoil checks for vehicles; being an improvement on the device for which Letters Patent were issued to me Jan. 16th, 1906, and numbered 810,282. In my former device the returning or recoil springs had to be made strong to permit the 10 grippers to move with every slight movement of the frame of the car in order that said grippers might take hold firmly whenever the car received a sudden jolt. This continuous movement of the grippers and 20 the friction against the inner wall of the cylinder or casing incident to such movement, soon wore the frictional face of the grippers to the extent that they would not always hold.

My present improvement consists in employing suspension springs between which the gripping device is held or suspended, so that, these suspension springs will sustain the weight of the car. In other words, these 30 suspension springs maintain the body of the car normally in a horizontal line, and thus permit the wheels to follow the slight irregularities of the road bed with the device moving vertically to follow these irregularities 35 while the grippers remain stationary. But when there comes a sudden jolt sufficient to compress the vehicle springs to a point where they are liable to be broken in the sudden rebound, then the grippers will take hold 40 and prevent this sudden rebound by holding the compressed vehicle springs for a second, when the grippers will relax their hold and permit the vehicle springs to move slowly back to normal.

To enable others to understand my invention reference is had to the accompanying drawings in which:

Figure 1—represents a broken view of the vehicle or car frame, sectional view of one of the suspension spring cases and compound springs therein, sectional view of the recoil-check casing, grippers, and broken view of the connecting rod of the recoil device, and sectional view of the car axle; all the parts 50 being in a normal position. Fig. 2—is a cross

sectional view of one of the suspension spring cases, on line —a—a— of Fig. 1.

While the recoil check forms no part of my present invention, a brief description, however, will be given of its construction and 60 operation.

1—is the outer cylindrical shell or casing. 2—and 3—are the semi-circular grippers carrying the semi-circular cork packings 4—adapted to have frictional engagement 65 with the interior of the shell 1—. 5—and 6—are supports secured to said grippers. 7—and 8—are toggle arm levers journaled in said supports.

9—is a block having the transverse slot 70 10—therethrough to receive the free ends of the toggle arm levers. The lower threaded end of this block is screwed into the interiorly threaded coupling 11—, and 12—is the connecting rod whose upper threaded 75 end is also connected with said coupling.

13—and 14—are studs anchored to the top of the casing 1—whose lower ends carry the adjusting nuts 15—and 16—.

17—is a plate held normally in a horizontal 80 position and, at the same time, permitting the grippers to expand and contract. This plate has holes—not shown, therethrough to freely admit the studs 13—and 14—. 18—and 19—are springs loosely embracing 85 said studs and are located between the nuts 15—and 16—and the plate 17—and are normally compressed as shown.

20—is a chain connecting the lower end of rod 12—with the axle 21—. 90

22—and 23—are cylindrical shells secured to the central casing 1—. 24—and 25—are studs projecting within these shells for the purpose to be presently described. These studs are anchored in the 95 yoke 26—, which yoke is suspended from the hook 27—attached to the frame 28—of the vehicle. As the mechanism in both of the shells 24—and 25—are similar, a brief description of one will suffice.

29—is a coarse pitch spring located between the top of the shell and the base of the thimble 30—.

31—is a finer pitch spring located between the nut 32—of the stud 24—, and the 105 bottom of the thimble, thus making a compound spring.

In my former patent, as before mentioned, the recoil check was directly connected to the frame and axle and, consequently, the casing 110

—1— moved up and down with the axle for every slight vibration resulting from the slight irregularities of the road bed, and it was only when the vehicle springs were violently compressed that the grippers took hold to prevent a sudden rebound of said springs. This is not only made hard riding but it brought an undue wear on the grippers. In my present improvement, the car is suspended on the supplemental side springs of the recoil check, while the check itself is suspended on these side springs. This enables the wheels of the car to ride over any obstruction that would not compress the elliptic springs of the 15 car beyond a point calculated to insure easy riding and, at the same time, effect no independent vertical movement of the shell of the recoil check until after an undue and dangerous compression of the car springs has 20 taken place, and when such undue compression occurs, the stored up tension of the springs —18— and —19— will loosen the grippers to permit the shells —1—, —22— and —23— to descend, when the grippers 25 will instantly take hold to prevent a too sudden rebound of said car springs. The thimbles in the shells —22— and —23— not only serve as means for separating the compound springs but also keep said springs from being crushed or thrown out of alignment as when, under a sudden and heavy jolt, the thimbles are brought violently against the top of said shells.

Having thus described my invention what 35 I claim as new and desire to secure by Letters Patent is:

1. In a vehicle, the combination with a recoil check of the construction shown and described, of suspension springs, shells embracing said springs and contiguous to said check and by which said check is suspended, means for connecting said suspension springs with the frame of the vehicle, and the recoil check with the axle, for the purpose set forth.
2. In a vehicle, the combination with a recoil check adapted to arrest the sudden re-

turn of the vehicle springs after compression, said recoil check having grippers, a casing embracing said grippers, means for expanding said grippers under a sudden compression 50 of the vehicle springs to engage with the inner wall of the casing so as to temporarily check the recoil of the springs, means for connecting the recoil check with the axle, and side suspension springs to form a flexible support on 55 which said recoil check is suspended and independent of the body supporting springs for the purpose set forth.

3. In a vehicle, the combination with a recoil check adapted to arrest the sudden return of the vehicle springs after compression, said recoil check having a casing, expansible grippers therein, toggle arms connected with 60 said grippers, a connecting rod, means thereon to engage said toggle arms to expand the grippers, means to connect said rod with the axle, and a resilient support for the recoil check independent of the body supporting springs for the purpose set forth.

4. The combination, in a vehicle having 70 compressible springs, of a recoil check adapted to arrest the sudden recoil of said springs after compression, said recoil check having a casing with expansible grippers therein, toggle arms connected with said grippers, a connecting rod engaging with said grippers, means for connecting said rod with the axle, shells secured to said casing, suspension 75 springs in said shells, studs projecting within said shells and supporting the suspension springs, a yoke in which said studs are anchored, and means for connecting the yoke with the vehicle frame, for the purpose set forth.

Signed at Bridgeport in the county of 85 Fairfield and State of Connecticut this 14th day of Jan. A. D. 1907.

HENRY A. HOUSE.
